UNITED STATES PATENT OFFICE.

PHILIP E. EDELMAN, OF CHICAGO, ILLINOIS, ASSIGNOR TO EPHRAIM BANNING, OF CHICAGO, ILLINOIS.

POWER-UNIT RELAY SWITCH.

Application filed November 25, 1927. Serial No. 235,613.

My present invention relates to an automatic switch for operating electrical devices and more particularly is suited for the automatic operation from a radio receiving set filament control switch of a power supply unit which contains no battery such for example as a battery eliminator of the class disclosed in my pending application for United States Letters Patent Serial No. 10 163,734, filed Jan. 26, 1927. An object is to start and stop the power flow to the power unit when the radio set switch is turned on and off so that no electric current is consumed in the power unit when the radio 15 set is not in use. A further object is to accomplish this by means of a relay switch which requires no change in the wiring of the power unit itself but can be externally attached thereto if so desired. Other 20 objects will presently appear.

wire 13. When however, coil 47 is energized as hereinafter set forth, switch arm 40 causes contact 49 to break from contact 48 and make contact 50 with contact 51, thereby disconnecting primary coil 15 and causing current to flow via spring 43, wire 8, and socket 7, connecting to wire 13 via wire 9, and energizing power unit 1 connected at socket 7. Thus, either coil 15 will be energized while power unit 1 is not, or vice versa. Coil 15 65 of transformer 14 however consumes negligible current because secondary coil 16 is normally not supplying current except the momentary amount required to initially energize coil 47 when a load is first connected 70 to terminals 5 and 6. Switch arm 40 has sufficient return force to restore contact 49 closed against contact 48 when coil 47 is not carrying current.

I attain these objects by means of a relay switch and circuit therefor, of which a suitable example is shown in the accompanying drawing, in which, Figure 1 is a diagram showing the relay switch and its circuits, and Figure 2 is a side view of the iron core 24 and shade ring 27 projected therefrom.

My relay switch starts operating on alternating current obtained from a small bell ringing transformer 14 and continues its operation by means of the direct current supplied immediately by the power unit 1, whereupon the transformer 14 is disconnected during the use of power unit 1 and causes no ripple current to reach output terminals 5 and 6.

The power unit 1 may be of any type employing no battery and has the usual output terminals 2, 3 and input plug 4. The relay switch I provide can attach to input plug 4 and output terminals 2, 3, without disturbing unit 1.

A socket 10 attached to an alternating current lighting main supplies the primary power, and the plug connector 11 serves to connect the unit 1 and the relay switch to this source of power 10. Wires 12, and 13 connect as shown via either socket 7 or primary winding 15 of transformer 14, according to the position of switch arm 40. When relay coil 47 is not energized, switch arm 40 causes contact 49 to remain closed against contact 48 so that current flows via spring 44, wire 20 and primary coil 15 to

wire 13. When however, coil 47 is energized as hereinafter set forth, switch arm 40 causes contact 49 to break from contact 48 and make contact 50 with contact 51, thereby disconnecting primary coil 15 and causing current to flow via spring 43, wire 8, and socket 7, connecting to wire 13 via wire 9, and energizing power unit 1 connected at socket 7. Thus, either coil 15 will be energized while power unit 1 is not, or vice versa. Coil 15 65 of transformer 14 however consumes negligible current because secondary coil 16 is normally not supplying current except the momentary amount required to initially energize coil 47 when a load is first connected 70 to terminals 5 and 6. Switch arm 40 has sufficient return force to restore contact 49 closed against contact 48 when coil 47 is not carrying current.

Secondary coil 16 of transformer 14 connects to relay coil 47 via wire 18 and also connects via wire 17 to spring 41 carrying contact 55. Switch arm 39 carries contact 54 normally open from contact 55.

Switch arm 39 connects via wire 21 to coil 16 of transformer 14. Contact 53 carried by switch arm 39 normally is closed to contact 52 carried by spring 42. Spring 42 connects via wire 56 to wire 58 and to negative output terminal 5 and negative terminal 85 2 of power unit 1 via wire 58. Contacts 53 and 52 thus closed, normally short circuit the output terminals 2, 3, of power unit 1 so that the tendency of alternating current to flow back thru unit 1 from secondary winding 16 of transformer 14 is negligible. But a circuit is provided to energize coil 47 from transformer secondary 16 via switch arm 39 and spring 42 when a load is applied to output terminals 5 and 6. Terminals 5 and 6 95 can be carried by a mounting strip 22 for convenience. When, however, coil 47 is energized by transformer 14 on closing a load across terminals 5 and 6, switch arm 39 is caused to open contact 53 away from contact 52 and to close contact 54 against contact 55, thereby short circuiting transformer coil 16 via said shunt contacts 54 and 55 and permitting current to flow via wires 57 and 58 from unit 1 thru coil 47 to the load applied to terminals 5 and 6. All tendency toward ripple current in the load applied to terminals 5 and 6 from transformer 14 is thereby avoided while the resistance inherent in winding 16 of transformer 14 is 110

thereby cut out. When load current ceases thru coil 47, switch arm 39 again closes contact 53 against contact 52. The closing of contacts 54 and 55 thus short circuits winding 16 via wires 17 and 21.

Coil 47 connects via wire 19 to output terminal 6. Coil 47 also has a portion of its turns short circuited at all times by wire 46. This is done to cause a certain time lag in 10 the operation of the switch arms 39 and 40, and also to reduce the impedance of coil 47 to alternating current which flows there thru from transformer 14, so that a greater pull is obtained on armature 30 when coil 15 47 is energized with alternating current.

When coil 47 is energized, it magnetizes iron core 24 and causes armature 30 to be pulled toward core 24. The flow of alternating current thru coil 47 tends to make 20 this pull on armature 30 unsteady as the distance between armature 30 and core 24 is reduced, so I introduce at one end of core 24, a heavy ring 27 or shade ring. This ring 27 in effect becomes a short circuited 25 secondary winding when coil 47 is energized by alternating current and sets up a flux at a portion of core 24 at the end thereof which remains during the brief time that the flux set up thru core 24 by winding 47 30 is passing thru zero value. This tends to steady the pull on armature 30 sufficiently for satisfactory operation. The end view of core 24 shown in Figure 2 illustrates a suitable position for the ring 27.

35 Ring 27 is carried in a slot 29 in one end of core 24 and insulated therefrom by insulation 28. Ring 27 has no detrimental effect to the operation of coil 47 on direct current supplied from unit 1 via wires 57 40 and 58. Chattering of armature 30 is thereby avoided and undesired sparking at contacts 48, 49, 50, 51, also 52, 53 and 54, 55 is minimized.

Core 24 of relay switch 23 has a yoke 45 25 fastened thereto at 26. Yoke 25 supports an insulating mounting 45 which carries springs 41, 42, 43, 44 and switch arms 39 and 40 insulated from each other at this support.

50 Switch arm 39 carries an insulator pin 38 positioned adjacent to an insulator pin 37 attached to switch arm 40. Switch arm 40 also carries an insulator pin 36 adjacent to insulator pin 35 which is fastened to arm 55 31 comprised with armature 30. A projection 34 on arm 31 limits the return travel of arm 31 under the return force of switch arms 39 and 40. A pivot or shaft mounting 32 is supported from yoke 25 by support 33 and permits arm 31 to move under the control of the pull on armature 30 by core 24, or the return force from switch arms 39 and 40 which is made sufficient for the purpose to restore projection 34 against yoke 25 when coil 47 is not energized.

When coil 47 is energized, armature 30 is pulled and causes arm 31 to move switch arms 40 and 39 in a sequence via pins 35, 36, 37 and 38.

The relay 23 is thus controlled wholly 70 under the condition of a load applied to terminals 5 and 6 or no load attached thereto. When load is first connected to terminals 5, and 6 power unit 1 is not energized until coil 47 has been energized by 75 transformer 14, so that momentarily alternating current from winding 16 passes thru coil 47 thru the load circuit attached to terminals 5 and 6 sufficient to pull armature 30 towards core 24. The impedance 80 of power unit 1 does not prevent this pull because wires 57 and 58 are at the start short circuited via contacts 53 and 52. The first pull on armature 30 however energizes power unit 1 and operatively permits current to flow thru coil 47 via wires 57 and 58 to maintain the operation as long as a load circuit is attached to terminals 5 and 6. There is accordingly only a brief period 85 during which alternating current can flow 90 at terminals 5 and 6 and this period is so brief that no hum will be heard in the reproducer of the radio set connected to terminals 5 and 6. Relay 23 thus starts on alternating current but operates thereafter 95 on the current supplied from unit 1 which is caused to receive energizing current via plug 4 under control of the relay 23. The load circuit attached to terminals 5 and 6 thus controls the operation of relay 23 so 100 that no energizing current flows thru power unit 1 from socket 7 except when power unit 1 is supplying load current via terminals 5 and 6.

The invention thus resides in the new and 105 useful combination of elements producing the new result sought for, which is thereby attained in practical and useful manner without requiring the use of any battery current or rectified current for starting and 110 without introducing undesired ripple current in the load circuit attached to terminals 5 and 6. Various changes and modifications may be made without departure 115 from the invention set forth and within the scope of the appended claims.

I claim:

1. A power unit relay switch including an actuating coil electromagnet, means to start the operation of said switch on alternating 120 current supply, means to reduce the impedance of said coil to the flow of alternating current therethru, means to maintain the operation of said coil by direct current flowing therethru, and means to retard the magnetic pull of said coil electromagnet during the transfer of the operation thereof from alternating current to direct current.

2. A power unit relay switch including 125 terminals attachable to the input and out- 130

- put terminals of a power unit, a starting power supply for said relay switch, switch contacts operated by said relay switch and permitting power to flow from said power unit, cooperating contacts, operating when said power flows from said power unit, to maintain the operation of said switch contacts, and means to steady the operation of said switch contacts during the time that 5 operation thereof is transferred from the starting power supply to the maintaining power flow from said power unit.
3. A power unit relay switch comprising terminals attachable to a radio power supply unit at the input and output terminals 15 of said unit, a separate starting power supply to actuate said switch, means to continue the operation of said switch on power obtained from said power supply unit, and 20 contacts controlled by said switch to disconnect said starting power supply therefrom when said power supply unit is operated by said switch.
4. A power unit relay switch consisting of input and output feeders for a power unit, a transformer to start the operation of said switch, contacts controlled by said switch to short circuit said output feeders during the instant that said transformer is 25 actuating said switch, cooperating contacts controlled by said switch to transfer the continued operation of said switch on power obtained from said power unit, and contacts to by-pass said transformer so that no energy flows therefrom to said output feeders 30 when said power unit is operated.
5. A power unit relay switch consisting of an electromagnet having some of its coil turns short circuited, an armature pulled by 35 said electromagnet, a transformer to start the pull of said electromagnet, means to steady said starting pull, a sequence of switch contacts actuated by the pull on said armature, and circuits controlled by said 40 switch contacts to operate a power supply unit and maintain the operation thereof from power obtained from said supply unit.
6. A power supply unit relay switch consisting of an electromagnet, an armature actuated thereby, a sequence of contacts operated by said armature, a starting transformer to energize said electromagnet, a power unit energized under control of said contacts, means to transfer the operation of 45 said electromagnet from said transformer to said power unit, and means to transfer said transformer out of service while the operation of said electromagnet is accomplished by said power unit.
7. A power supply unit relay switch consisting of input and output feeders for a power unit, an electromagnet, a separate transformer to actuate said electromagnet, an armature pulled by said electromagnet, a sequence of contacts controlled by the pull on said armature, and circuits included by and connecting to said contacts to feed energy to said power unit, and to disconnect said transformer from said electromagnet when said power unit is energized. 50
8. A power supply relay switch consisting of a double pole double throw switch including contacts controlled by an electromagnet, a transformer and a power unit alternately operated according to the position of one pole of said switch, and connections to the other pole of said switch to short circuit the output terminals of said power unit while said transformer is energized and to render said transformer inoperative while 55 said power unit is energized whereby said electromagnet is operated either by said transformer or said power unit according to the position of said switch, and means to maintain magnetic flux in said electromagnet during the transfer of the operation thereof from said transformer to said power unit. 60
9. A power supply relay switch attachable to a power unit consisting of an input 65 socket and an output terminal connector for said power unit, an electromagnet, a transformer to actuate said electromagnet, switch contacts operated by said electromagnet, and connections to said contacts to supply energy to said input socket when a load circuit is connected to said output terminal connector and to cut off the energy input at said input socket when said load circuit is disconnected from terminal connector, and means to cut off the operation of said transformer during the time that said load circuit is operated by said power unit. 70
- In witness whereof I have hereunto set my hand and seal this 20th day of November, 1927.
- PHILIP E. EDELMAN. [L. s.]
